MULTI-ANGLE GLOSSMETER

Matthew A. Cattaro, Great Falls, Va., Gilbert L. Gibson, Chevy Chase, Md., and Americo J. Giovannoni, Washington, D.C., assignors to Gardner Laboratory, Inc., Bethesda, Md., a corporation of Maryland

Filed Mar. 1, 1962, Ser. No. 69,040

Term of patent 7 years

(Cl. D52—6)

Fig. 1.

Fig. 2.

Fig. 3.

FIG. 1 is a front elevational view of a multi-angle glossmeter, showing our new design.

FIG. 2 is a view in side elevation; and

FIG. 3 is a top plan view.

The undisclosed side of the glossmeter is substantially the same in appearance as the side shown, and the rear is substantially plain and unornamented.

We claim:

The ornamental design for a multi-angle glossmeter, as shown and described.
